The ornamental design for a wall-mounted display for ticket stubs, as shown and described.

DESCRIPTION

FIG. 1 is a front elevation view of the wall-mounted display for ticket stubs;

FIG. 2 is an elevation of the top end of the display, wherein the elevation of the bottom end is a mirror image of FIG. 2; FIG. 3 is an elevation view of the left side thereof, wherein the right side elevation is a mirror image of FIG. 3; and, FIG. 4 is a rear elevation view thereof.

The broken lines are for environmental purposes only and form no part of the claimed design.
